Joseph Cooper, New York, N. Y.

Application October 14, 1939, Serial No. 299,500

2 Claims. (Cl. 311—45)

The object of the present invention is to provide an extensible table comprising a fixed and concealed center leaf when the table is closed, which leaf remains motionless during the extension of the tables which is effected by moving outward two leaves which normally conceal the center leaf followed by a slight inward movement.

The invention will be described with reference to the accompanying drawings, in which—

Figure 1 is a bottom plan view of a table embodying the invention.

Figure 2 is a sectional elevation of Figure 1, on the line 2—2;

Figure 3 is a transverse section on the line 3—3, Figure 2.

Figure 4 is an enlarged fragmentary elevation showing a cam plate and its mode of connection with one of the slide bars which carries a movable leaf.

Figure 5 is a view similar to Figure 2 showing the position of a movable leaf at the end of its outward movement preliminary to inward movement for final positioning.

Figure 6 is a view similar to Figure 5 showing the position of the parts when said movable leaf has been extended, moved inwardly, and finally positioned.

Figure 7 is a perspective view showing one end of the table with its movable leaf removed from the slide bars which normally carry the same.

Referring to the drawings, I have shown at 1 the vertical legs or supporting members for a frame comprising the longitudinal rails 2 and the transverse or end rails 3.

At the center of the frame, extending transversely thereof, and mounted upon the longitudinally extending rails 3 is a fixed top member 4. Secured to the underface of top member 4 are two sets of cam plates, the first set being indicated at 5 and the second set at 5x. Each set of cam plates may be secured at one end to the appropriate transverse rail 3 of the frame.

Normally lying over and concealing fixed top member 4 are two movable top members 6 and 7. If desired, they may be provided with drop skirts 6x and 7x, respectively.

Carried by the movable top member 6 at its underface are two spaced slide blocks 8 which extend longitudinally of said top member. Each slide block 8 carries a pair of headed studs entering two cam slots formed in the appropriate one of the pair of cam plates 5, the headed studs being indicated at 9. Each cam plate 5 is formed with a guide slot at 10 with a combined guide

and latch slot at 11, the latter having a slot under a latch projection 5x.

When the movable leaf is in the position of Figures 1 and 2 and is moved outwardly the studs 9 of the slide block 8 will approach downwardly inclined sections of the cam slots 10 and 11 and will finally move down these inclines causing a tilting of the table to the position of Figure 5. In such position, headed stud 9 will lie below cam slot 11 will be positioned immediately ahead and forwardly of latch projection 5x, as to each of the cam plates and slide blocks. Movable leaf 6 may be tilted to horizontal position and moved into abutment with fixed leaf 4, this movement carrying the inner studs 9 under the latch projections 5x.

It will be understood that in the restoring of leaf 6 to the position of Figure 2 the leaf will be moved outwardly to carry the appropriate studs 9 outwardly of the latch projections 5x whereupon the leaf is tilted to the position of Figure 5 and moved inwardly over fixed leaf 4 until leaf 6 and leaf 7 lie in abutment.

The operation of movable leaf 7 is exactly the same as that of leaf 6 and the cam plates 5x are operated in conjunction with slide blocks and headed studs of the same construction as those shown with reference to leaf 6 and therefore bearing the same reference numerals.

If desired, the leaves 6 and 7 may lightly be held into abutment either with themselves or with the fixed leaf 4 through the pressure of light springs 13, Figure 1, but this is not essential.

Having described my invention, what I claim and desire to secure by Letters Patent, is as follows:

1. In a table, a supporting frame, a fixed leaf carried by the frame centrally thereof, two edge-wise movable leaves normally in edge abutment and disposed over and concealing the fixed leaf and a cam control device for each of said movable leaves, said cam control comprising a plate formed with two substantially parallel channelways and an inclined channelway connecting the parallel channelways, a latch projection being formed intermediate the parallel channelways, a block depending from the movable leaf, and an element projecting laterally of the block and entering the said channelway formation, said element resting on a channelway area below the latch projection when the appropriate edge-wise movable leaf is in edge abutment with the fixed leaf.

2. In a table, a supporting frame, a fixed leaf

carried by the frame centrally thereof, two edge-wise movable leaves normally in edge abutment and disposed over and concealing the fixed leaf, a block projected downwardly from each movable leaf and a pair of studs projected laterally therefrom and a cam control device for each of said movable leaves, each cam control device being a plate carried below its appropriate movable leaf and formed with two cam channelways each channelway receiving one of said studs, each channelway extending longitudinally of the

plate, and having three sections, to wit, two vertically spaced substantially horizontal sections and an inclined section joining the two horizontal sections, and a latching projection contiguous at least one of said channelways and acting as an overhanging member for one of said studs to restrain the appropriate edgewise movable leaf against tilting when said leaf is in edge abutment with the fixed leaf.

10

JOSEPH COOPER.
